UNITED STATES PATENT OFFICE.

JOSEPH ELCOCK, OF MECHANICSBURG, PENNSYLVANIA.

GATE.

SPECIFICATION forming part of Letters Patent No. 471,851, dated March 29, 1892.

Application filed November 27, 1891. Serial No. 413,300. (No model.)

To all whom it may concern:

Be it known that I, JOSEPH ELCOCK, a citizen of the United States, residing at Mechanicsburg, in the county of Cumberland and 5 State of Pennsylvania, have invented new and useful Improvements in Gates, of which the following is a specification.

This invention relates to improvements in that class of gates that are arranged to slide 10 on and between rollers that are supported by the gate-posts; and it consists in the construction and combination of parts in a sliding gate, as hereinafter more fully described, and particularly pointed out in the claims.

15 In the annexed drawings, illustrating the invention, Figure 1 is a perspective of my improved sliding gate, showing the same as it appears when open. Fig. 2 is a vertical cross-section through the line 2 2 of Fig. 1, showing 20 the vertically-adjustable roller-bearing box for raising and lowering the end of the gate to give it a proper set. Fig. 3 is a vertical cross-section through the line 3 3 of Fig. 1, showing more clearly the grooved chain-wheel 25 or double pulley and its crank-shaft for actuating the gate. Fig. 4 is a view of a modified arrangement of devices for revolving the pulley-shaft. Fig. 5 is a detail view of a portion of the forward end of a gate, showing the gate-30 stile extended upward and carrying a roller to run on a rail or cross-bar connecting the upwardly-extending ends of two gate-posts.

Referring to the drawings in detail, the numeral 1 designates the gate proper, which is 35 composed of the usual stiles and longitudinal bars that may be suitably braced in any convenient manner, as shown.

The numeral 2 designates the latch-post, which is provided with vertical flanges 3 on 40 the side toward the adjacent end of the gate, thus forming a vertically-elongated recess 4, into which one of the gate-stiles enters when the gate is closed. At the foot of this recess 4 is an anti-friction roller 5, that facilitates 45 engagement of the gate with the latch-post.

The main gate-post 6 is made double or composed of two standards having their inner faces provided with vertical guideways 7 for receiving a vertically-elongated and vertically-adjustable box 8, in the opposite ends 50 of which are journaled the flanged guide-rolls-

ers 9, between which the gate 1 is mounted, and along which the upper and lower longitudinal bars of the gate are enabled to slide freely and easily in opening and closing the 55 gate. On the top of the double post or twin standards 6 is secured a plate or cross-piece 10, having a central screw-threaded aperture for passage of a screw-threaded crank-shaft 11, that is loosely connected with the upper 60 end of the vertically-adjustable box 8, in which the rollers 9 are mounted. By turning the screw-shaft 11 in the proper direction the rollers 9 can thus be raised or lowered, as required, for the purpose of imparting the de- 65 sired set to the gate, so as to enable it to be operated with ease.

At one side of the gate 1, between the latch-post 2 and main post 6, is arranged an intermediate post 12, to which is secured a bracket 70 13, in the upper and lower ends of which are journaled flanged guide-rollers 14 above and below the upper and lower longitudinal gate-bars, respectively, to assist in supporting and guiding the gate. The post 12 and bracket 75 13 also support a rotary shaft 15, on which, between said post and bracket, is securely mounted a double-grooved wheel or pulley 16 for attachment of chains or ropes 17, that are extended to the opposite ends of the gate and 80 secured thereto in any suitable manner. The attachment of these ropes or chains 17 to the opposite ends of the gate may be effected either by means of screw-eyes 18 or eyebolts 19, as preferred, or by any other convenient 85 means. The grooved wheel or pulley 16 may be rotated by means of a crank-handle 21 on the pulley-shaft 15, as shown in Fig. 3, or, as shown in Fig. 4, the crank may be replaced by a double-grooved wheel 22, having attached 90 thereto ropes 23, passed over pulleys 24 at the top of the post 12 and carrying weights 25 at their free ends, so that by pulling down on one of said ropes it will be unwound from the wheel 22 while the other weighted rope 23 is 95 wound thereon. By means of these weighted ropes 23 and grooved wheel 22, or by means of the crank 21, as the case may be, the shaft 15 and double-grooved wheel 16 may be rotated in the desired direction to open or close 100 the gate. When the gate is moved in either direction, as above described, one of the chains

17 will be unwound from the grooved wheel 16 as the other chain is wound thereon by the turning of the wheel and its shaft.

As shown in Fig. 5, the gate-posts 2 and 12 5 may be extended upward and connected by a rail or cross-bar 26 to support a roller 27 on the upward-extended end of the forward gate-stile, thereby further facilitating the opening and closing of a heavy gate. The rail or cross-bar 26 should be supported at a sufficient height to permit the passage of vehicles.

It will be seen that the described arrangement of the sliding gate and its operating mechanism is such as to enable the gate to be 15 readily opened and closed without the exertion of any great amount of strength or power, owing to the smoothness with which it will move in its bearings or supports. When closed, the gate is firmly and staunchly supported, and when open it exposes almost the 20 entire width of the roadway for the passage of vehicles.

What I claim as my invention is—

1. The combination, with a latch-post 2, a 25 main gate-post 6, comprising two parallel standards having guideways at their inner sides, and an intermediate post 12, having upper and lower guide-rollers 14, of a vertically-sliding roller-box 8, engaged with the 30 guideways of the standards and provided with upper and lower guide-rollers 9, a cap-plate 10, connecting the upper ends of the standards

and having a screw-threaded orifice, and a rotating screw-shaft 11, engaging the threaded part of the cap-plate, provided with a crank-handle, and loosely connected with the upper end of the roller-box, substantially as described. 35

2. The combination, with a latch-post 2, a main gate-post 6, comprising two parallel 40 standards having guideways at their inner sides, a sliding gate 1, and an intermediate post 12, having upper and lower guide-rollers 14, and a rotating grooved wheel provided with a rope wound thereupon and connected 45 with opposite ends of the gate, of a vertically-sliding roller-box 8, engaged with the guideways on the main gate-post and provided with upper and lower guide-rollers 9, a cap-plate 50 10, secured to the main gate-post and having a screw-threaded orifice, and a rotating screw-shaft 11, engaging the threaded part of the cap-plate, provided with a crank-handle, and loosely connected with the upper end of the roller-box, substantially as and for the purposes described. 55

In testimony whereof I have hereunto set my hand and affixed my seal in presence of two subscribing witnesses.

JOSEPH ELCOCK. [L. S.]
